(57) **CLAIM**

The ornamental design for a sterile cover, as shown and described.

DESCRIPTION

FIG. 1 is a top perspective view of a sterile cover, showing my/our new design;

FIG. 2 is a front elevational view thereof;

FIG. 3 is a back elevational view thereof;

FIG. 4 is a left elevational view thereof;

FIG. 5 is a right elevational view thereof; and,

FIG. 6 is a top plan view thereof.

The broken lines show portions of the design that form no part of the claimed design.

Bottom views are omitted from the embodiments shown in FIGS. 1-6 because the bottom is flat and devoid of surface ornamentation.
